EXTENSION DEVICE HOLDER AND POSITIVE
SNAP LOCK

Minard P. Baker, Salem, Mass.

Application January 15, 1951, Serial No. 206,085

3 Claims. (Cl. 248—223)

1

This invention comprises novel and useful improvements in an extension device holder and positive snap lock and more specifically pertains to a device for supporting tools or similar apparatus outwardly from a work bench.

The primary object of this invention is to provide a simple extension or platform to which apparatus such as a meat grinder can be securely attached with no resulting damage to the household furniture or fixture to which the meat grinder or device would ordinarily be directly fastened.

Another very important object of this invention is to provide a locking mechanism containing a means for clamping a bar, hook or the like therein.

Another object of this invention is to provide an extension platform for meat grinders and the like which may be easily collapsed when not in use and likewise assembled when its use is desired.

Yet another object of this invention is to provide a platform or stand extended outward from the member to which it is attached and which contains a device for locking the platform in a horizontal position.

A still further object of this invention is to provide an extension device holder which may be easily adapted to fit on the conventional parts of a meat grinder.

Other objects and features of this invention are to be found in an extended platform for supporting meat grinders and the like which is simple in construction, inexpensive to manufacture, convenient to operate and which is compact in structure thereby enabling ready and convenient storage.

These, together with various ancillary features and objects of the invention, which will later become apparent as the following description proceeds, are attained by the present invention, a preferred embodiment of which is illustrated, by way of example only, in the accompanying drawings, wherein:

Figure 1 is a perspective view of the extension platform or bracket comprising this invention;

Figure 2 is a vertical sectional view taken along the plane of the section lines 2—2 of Figure 1;

Figure 3 is a side vertical view of the invention as seen in Figure 1, but illustrating the invention in a collapsed form;

Figure 4 is a horizontal sectional view taken along the plane of the section lines 4—4 of Figure 1;

Figure 5 is a perspective view of a portion of

2

the invention and illustrating in particular the various elements of the snap lock in a disassembled arrangement;

Figure 6 is a vertical side view illustrating the adaptation of the present invention to a meat grinder; and

Figure 7 is a perspective view illustrating the inner stepped portion of the support member.

Referring now more specifically to the accompanying drawings, wherein like numerals designate similar parts throughout the various views, it will be noted in Figure 6 that the numeral 10 denotes generally a table or other similar article of household furniture. As is the conventional mode of practice, the meat grinder 12 is supported in such a fashion as to permit the mouth or discharging end 14 of the grinder to extend over the upper surface of the table 10. Generally, meat grinders are provided with some clamping mechanism by which they are secured to the platform over which they will operate and it is well known that such clamping action will, in time, mar or damage the areas of the tables against which it bears. Accordingly, it is an object of this invention to provide a device or extension platform to which the jaws of a meat grinder may attach, thereby permitting this platform to absorb the wear of the clamping jaws or alternately, to provide an extension device which may be adapted to the meat grinder in such a fashion that no clamps are needed.

With the foregoing as a background, attention should be directed to Figure 1 wherein it will be noted that the extension device, per se, includes a vertically mounted wall plate 16 constructed of a rigid metallic material or the like and being attached to the wall 18 by means of screws 20. In proximity to the upper edge of the plate 16 is a horizontal rod 22 having its end slightly curved whereby the same may be welded or rigidly secured to the plate. Therefore, by such an arrangement, an opening 24 is provided between the rod 22 and the plate 16.

The stepped support member 26 is pivotally attached to the rod 22 by means of the hooks or fingers 28 integrally extending from the lower stepped portion 30 of the member 26.

The upper level or step 32 of the support member 26 comprises a platform to which a meat grinder or similar device may be attached. A block 34 is provided on top of the platform 32 and is secured thereto by means of the screws or bolts 36. In this manner, the clamps or jaws of a meat grinder or the like may be easily attached to the platform and furthermore, when

the block becomes damaged, the same may be easily replaced.

Since it is necessary to maintain the supporting member 26 or more specifically, the platform 32 in a horizontal position, a substantially U-shaped brace 38 is provided having its ends bent for reception in a pair of depending eyelets 40 on the bottom of the platform 32. This brace is freely journaled in these eyelets and when it is desired to set the device in an operable position, the web portion 42 of the U-shaped brace is placed in the locking mechanism, generally denoted by the numeral 44.

The construction of the locking mechanism 44 is seen more clearly in Figure 5 and includes generally a keeper 46 and a latch 48. The keeper 46, as adapted to the instant invention, consists of a narrow plate 50 either rigidly embedded within the plate 16 or preferably, integrally a portion thereof. Further, the keeper 46 includes a pair of ears 52 extending forwardly from the lateral ends of the plate 50. These ears are constructed to resemble jaws having a depending nose 54 at the outer portion thereof and receding inwardly and upwardly forming an arcuate groove 56.

The latch 48 consists of a channel-shaped element having a back portion 58 and a pair of forwardly extending flanges 60, each of the flanges 60 is of a general irregular shape having an arcuate groove 62 provided in substantially the mid portion of the flange and being complementary to the groove 56.

To assemble the locking mechanism, it is necessary to place the latch with its flanges 60 received between the ears 46 of the keeper 50 and aligning thereby the apertures 64 and 66 provided in the latch and keeper, respectively. A bolt 68 is then placed through the apertures 64 and 66 thereby pivotally connecting the latch and keeper. In order that the latch will be urged inwardly towards the keeper pivoting in a counter-clockwise direction, a conventional spring 68 is provided having its legs bearing against the plate 16 and the inner surface of the back portion 58 of the latch 48.

It is believed that it will now be clearly apparent that in operation, the support member 26 is integrally engaged on the horizontal rod 22 by means of the hooks 28, the legs of the U-shaped brace 38 are then journaled within the eyelets 40 and the web 42 of this brace is finally placed in the arcuate grooves 56 whereby the latch 48 may be allowed to bear up against the plate 50, the grooves 62 engaging the lower surface of the web 42.

In the event that it is desired to incorporate the extension device directly to a meat grinder or the like, the arrangement is similar to that illustrated in Figure 6. Accordingly, as in the previous embodiment, a plate 70 is provided together with a locking mechanism 72 and a U-shaped brace 74. Attached to the lower end or base of the meat grinder 12 is a horizontal platform 76 having depending eyelets 78 at one end thereof and a depending flange 80 at the other end. Bolted or integrally secured to this depending flange 80 is a lower stepped portion 82 having at the lower level thereof the forwardly extending hook portions 84 which are adapted for hinged engagement with the horizontal bar 86. It is believed evident from this description that this alternative method will be understood.

From the foregoing, the construction and operation of the invention together with its many

advantages will be readily apparent, and further explanation is believed to be unnecessary. However, since numerous modifications and changes will readily occur to those skilled in the art after a consideration of the foregoing specification and accompanying claims, it is not desired to limit the invention to the exact construction shown and described and accordingly all suitable modifications and equivalents may be resorted to, falling within the scope of the appended claims.

Having described the invention, what is claimed as new is:

1. A snap lock comprising a keeper consisting of a narrow plate having a pair of forwardly extending ears, a latch comprising a channel shaped element having its flanges pivotally connected between said ears, said ears and flanges having complementary arcuate jaws formed thereon for engagement of a rod therebetween and means for yieldably urging said latch against said keeper, said jaws having complementary extensions and grooves therein whereby the jaws are inter-engaged with one another.

2. An extension bracket comprising a vertically mounted wall plate, a support member having a horizontal platform thereon and being hingedly attached to said plate, a locking mechanism disposed on said plate beneath said support member and a U-shaped brace removably secured between said locking mechanism and said support member, said locking mechanism comprising a keeper on said plate and a latch pivotally urged into engagement with said keeper, resilient means biasing said latch and keeper into locking engagement with said U-shaped brace, said keeper including a pair of spaced, parallel ears extending outwardly from said plate, said ears having hook-shaped ends, said latch being pivoted between said ears and having complementary hook shaped portions slidably closing said hook shaped ends, the web portion of said U-shaped brace being received between said hook ends and said complementary hook shaped portions.

3. An extension bracket comprising a vertically mounted wall plate, a support member hingedly attached to the upper end of said plate, a U-shaped bracket pivotally secured to said support member, a locking mechanism disposed on the lower end of said plate releasably securing said U-shaped brace between said support member and said locking mechanism thereby holding said support member in a fixed position, said locking mechanism including a keeper on said wall plate, said keeper having a pair of parallel, spaced, ears extending perpendicularly from said wall plate, said ears having downwardly extending arcuate shaped grooves thereon, the web of said U-shaped brace being received in said grooves, said latch being pivoted between said ears, extensions on said latch slidably closing said grooves and engaging the web of said U-shaped brace, means yieldingly urging the latch extensions into engagement with said grooves.
